[57] CLAIM

The ornamental design for a potted plant hanger, as shown and described.

DESCRIPTION

FIG. 1 is a perspective view of a potted plant hanger showing my new design, the portion of a bracket and pot being shown in broken lines for illustrative purposes only;

FIG. 2 is an enlarged fragmentary elevational view of a section of the rope which is partially shown in FIG. 1, it being understood that this pattern repeats uniformly throughout the length of the rope elements.
